UNITED STATES PATENT OFFICE.

THERON L. CAUDLE, OF WADESBORO, NORTH CAROLINA.

GARMENT SUPPORTER.

Application filed September 28, 1920. Serial No. 413,303.

To all whom it may concern:

Be it known that I, THERON L. CAUDLE, a citizen of the United States, and a resident of Wadesboro, in the county of Anson 5 and State of North Carolina, have invented certain new and useful Improvements in Garment Supporters, of which the following is a specification.

My invention relates to improvements in garment supporters, it being more particularly an improvement on the supporter disclosed in my co-pending patent application filed July 26, 1920, Serial No. 399,079, and it consists in the construction, combination 15 and mode of operation herein described and claimed.

One of the foremost objects of the invention is to provide a light and simple device for supporting trousers from the shirt of 20 the wearer, by which the use of suspenders may be dispensed with entirely and a belt worn for appearances only.

A further object of the invention is primarily to provide a resilient supporting 25 member, itself mounted on a firm yet pliable base which keeps the resilient member in its proper place and prevents the objectionable puckering of the trousers where it is mounted.

More specifically, a further object of the invention is to provide a garment supporter comprising a pliable base suitably mounted 30 on the inside of a pair of trousers, with a resilient supporting member stretched substantially between its extremities, the base preventing excessive contraction of said member and thereby avoiding the puckering 35 of the trousers which would otherwise occur were the provision of the base not made.

Other objects and advantages will appear in the following specification, reference being had to the accompanying drawings, in which:

Figure 1 is a perspective view illustrating the improved garment supported in place on the inside of a pair of trousers, it being understood that there is a corresponding supporter on the opposite side,

Figure 2 is an elevation of the simplest form of pliable base,

Figure 3 is an elevation of one form of resilient support stamped out of a flat piece of rubber,

Figure 4 is an elevation of a resilient sup-

port, molded to embody certain characteristics,

Figure 5 is a cross section of one of the eyelets of the supporter, taken on the line 5—5 of Figure 4,

Figure 6 illustrates another type of resilient support wherein a continuous spring is employed,

Figure 7 is an elevation of a spring support wherein a central strand is bared so as 65 to more readily engage the hook fixed on the shirt of the wearer,

Figure 8 is an elevation of a supporter employing a resilient cable,

Figure 9 is a front elevation illustrating 70 a modification in the pliable base, the ends of the resilient support being interlaced before fastening,

Figure 10 is a similar view showing another method of mounting the resilient sup- 75 port,

Figure 11 is a section on the line 11—11 of Figure 9,

Figure 12 is a front elevation of a pliable base somewhat on the order of that shown 80 in Figure 9, with a resilient support consisting of an elastic band,

Figure 13 is a view similar to Figure 12, illustrating another method of mounting the elastic band.

Figure 14 is a rear elevation of the base in Figure 13, showing how the elastic band is adjustably secured by a buckle.

Figure 15 is a detail perspective view showing the pliable base concealed in the 90 trousers band.

Figure 16 is a detail elevation of the pliable base of that form used in Figure 15, and

Figure 17 is a perspective view of a fur- 95 ther modification described below.

The fundamental principle of this invention may be briefly stated: It comprises the use of a resilient support 1, stretched between the extremities of the pliable base 100 2 and intended to be hung on the hook 3, carried by the shirt 4 of the wearer, so that the trousers 5 are supported on that side. There is one of the supporters, and a corresponding hook, on each side of the garments in question.

There are numerous modifications of both the resilient support and the pliable base. Some of these modifications have been illustrated in the drawings, and it is contemplat-

ed that even further modifications may be made, still keeping within the spirit of the invention. The base 2 can be made of any material suitable for the purpose, for example, of heavy celluloid, spring steel hickory wood, etc.

It has a slot 6 in each end, for the purpose of holding the base in place when sprung over the shanks of the buttons 7. 10 These buttons are exposed on the inside of the trousers as in Figure 1, but in the case in Figures 15 and 16, the base is concealed in the waistband of the trousers, being sewn in place with the buttons, which 15 latter are again exposed on the inside so as to enable fitting the resilient support thereover.

Were it not for the pliable base 2, the resilient support 1 would draw the buttons 20 7 together and cause an objectionable pucker in the trousers. The base having been mounted between the buttons, the resilient support is next fitted in place by introducing the buttons 7 to the eyelets 8 at each end.

25 In Figures 1 and 3, the support 1 consists of a piece of rubber stamped out into the shape shown in one operation, the eyelets and body are formed at the same time. In Figure 4, the support 1^a is molded into a peculiar shape.

The body between the eyelets is perfectly round, or substantially so, while the eyelets 8^a have the peculiar shape illustrated in cross sectional Figure 5. The material 35 tapers inwardly at 9 toward the buttonholes the inclined faces corresponding with the general shape of the button over which the eyelet is fitted.

Figure 6 illustrates the use of a firm coil 40 spring 10, the coil being undone at the ends to provide the wire loops 11. These are to be fitted over the buttons as in the previous cases. In Figure 7, the coil spring 10^a is separated in the middle to produce a single 45 strand 12. This strand when fitted over the hook 3 affords no occasion for the coil of the spring to separate, as might sometimes occur with the use of the straight coil spring support 10 in Figure 6.

50 In Figure 8, an elastic cable 13, with eyelets 14 formed by turning the ends back and clamping them at 15, constitutes the resilient support. Figure 9 illustrates a modification in both the form of the base 2^a, and the arrangement of the elastic support. The base is made broader than that in Figure 2, requiring an additional slot 16 for slipping the lower part of the base over a third button to hold the former down.

60 It is to be observed that the resilient support 17 is disposed considerably lower than in Figure 1. This arrangement gives a considerable latitude of arm movement of the wearer without drawing the elastic support 65 above the top of the trousers and thus ex-

posing it to view. The support is first slipped into slots 18 at the ends of the base, then interlaced through holes 19 before it is finally secured by means of knots 20 on the back as in Figure 11.

70 In Figure 10, the elastic support 17 is fitted across the base by simply inserting the ends into eyelets 21 and knotting them on the back. When adjustments in the support are to be made, as for example, when its tension is to be increased, either end may be drawn through farther in one of the eyelets and a second knot made therein.

75 Figures 12, 13 and 14 illustrate the use of an elastic band 22, the ends of which in the first instance, are laced between slots 23. In the second instance, the band is drawn between slots 24, at right angles to the direction of the band, a buckle 25 on the back enabling making adjustment for length, loss 80 in tension, etc. Although the base 26 in the three views referred to, is of a shape slightly different from that shown in Figure 9, it is 85 essentially the same.

90 It is contemplated that there may be instances when the base is to be concealed in the waistband of the garment so that only the elastic support remains visible. This arrangement has its advantages and it is illustrated in Figure 15.

95 Here the base 27 is very much like the first form in Figure 2, the slots in the first form being now replaced by simple holes or eyelets 28 through which the buttons 29 are 100 sewn to the garment. The elastic support 30, which may consist of any of the various forms thereof, is then stretched between the buttons 29 so that it has the appearance in Figure 15. The pliable base 27 prevents the garment from puckering between the 105 buttons.

Figure 17 illustrates a modification somewhat on the order of that shown in Figure 7, in that there is a straight part between two resilient sections. The elastic 31 is composed of a single band, which may consist of an elastic band or cable, doubled at 32 at the ends and there drawn through the slots in the base. A connecting piece 33 is fitted across the doubled ends of the band and is 110 for the purpose of preventing the elastic from unduly wearing or tearing as might be the case with the arrangement in Figure 12 for example.

115 The free ends of the elastic 31 are embraced by a buckle, through which necessary adjustments for loss in tension may be made. Instead of using a flat elastic band, an elastic cable on the order of that shown in Figure 9 may be used equally as well.

120 While the construction and arrangement of the garment supporter as herein described and claimed is that of a generally preferred form, obviously modifications and changes 125 may be made without departing from the 130

spirit of the invention or the scope of the claims.

I claim:

1. A garment supporter, comprising a pliable base with slots in the ends to enable springing over fastening means on the garment, and an opening in the bottom to receive other fastening means on the garment for holding the lower end down; and a supporting member fitted lengthwise of the base to enable fitting over fastening means on a garment between suitable openings, said member including means enabling adjustment thereof.
- 15 2. A garment supporter, comprising a suitable base, a single resilient element, with doubled ends on one side and secured on the other; and a connecting link fitted between the doubled ends.
- 20 3. A garment supporter, comprising a flexible base with slots open at the periphery of the base to enable springing the base over fastening means on a garment, a resilient element mounted on the base, fastened at one side of the base and having opposing doubled ends at the other side, and a connecting element between the doubled ends.
- 25 4. The combination of fastening means carried by an upper garment, cooperating supporting means carried by a lower garment comprising an elongated base, means on the lower garment with which the base is engaged to occupy a position transversely

of the garment, and a tension member mounted longitudinally of the base and 35 adapted to be fitted over the fastening means of the upper garment.

5. The combination of fastening means affixed to an upper garment, cooperating supporting means carried by a lower garment comprising an elongated base of resilient material, means in spaced-apart relation applied to the lower garment in the region of the waistband with which said base is engaged to occupy a position transversely of the garment and readily conform to the body of the wearer and against which means it is held by virtue of said resiliency, a tension member mounted longitudinally of said base, and a link inserted in said member 50 to take the wear when fitted over the fastening means of the upper garment.

6. The combination of fastening means carried by an upper garment, cooperating supporting means carried by a lower garment comprising an elongated base of resilient material, means in spaced-apart relation applied to the lower garment in the region of the waistband with which said base is engaged to occupy a position transversely of the garment and readily conform to the body of the wearer and against which it is held by virtue of said resiliency, and a tension member mounted longitudinally of 55 60 said base.

THERON L. CAUDLE.
